INVENTOR

BY *Victor J. Evans*

ATTORNEY

UNITED STATES PATENT OFFICE.

JOSEPH HILSER, SR., OF NEWARK, NEW JERSEY.

HAIR TRIMMER.

Application filed August 17, 1925. Serial No. 50,775.

My present invention has reference to a combined hair trimmer and comb.

My object is the provision of an article for this purpose characterized by simplicity in construction, cheapness in manufacture and thorough efficiency in practical use.

To the attainment of the foregoing, the invention consists in the improvement as 10 hereinafter described and definitely claimed.

In the drawings:—

Figure 1 is a perspective view of one embodiment of the improvement.

Figure 2 is a similar view of a second 15 form of the improvement.

Figure 3 is an end view of the construction illustrated in Figure 2.

As disclosed by the drawings my improvement contemplates the employment of 20 a flat body member 1 which has one of its ends merging into a handle 2. The flat body 1, on one of its edges, is formed with projecting teeth 3. These teeth are of a width to extend laterally beyond one of the faces of the body. The teeth are all of the same length, and the upper edges thereof are notched, as at 4. The notches are inclined toward the edge of the body on which the teeth are formed, and these aligning 25 notches provide a pocket for a cutting blade.

In Figure 1 of the drawings an ordinary razor blade 5 has its haft 6 pivotally secured, as at 7, to the handle 2 of the body. In this form of the device the improvement 35 may be successfully employed as a razor, comb, or as a hair trimmer. It will be apparent that when the cutting edge of the blade 5 is received in the notches 4 of the teeth 3, that by drawing the teeth through 40 the hair the said hair will be effectively trimmed. The depth of the cut is regulated by reversing the position of the device on the head of the person operated on. The inner edges of the teeth are closer to the 45 body, and when these edges are brought

against the hair the latter will be trimmed only slightly. A deeper cut is made when the opposite faces of the teeth are arranged against the hair.

In Figure 2, the body 1' has its edge opposite that formed with the teeth thickened in the direction of the teeth and this thickened portion, from the inner edge thereof is channeled longitudinally as at 10 to provide an outer flange 9. The channel also enters the body 1' so that the central portion of the body is thus thickened on the face thereof provided with the teeth and flange and this portion of the body will exert a pressure against a safety razor blade when the latter 50 is arranged between the flange and teeth to flex said blade and cause the edge thereof to tightly engage with the flange and teeth so that the blade will be effectively held on the body. 55

The simplicity of the construction and the advantages thereof will, it is thought, be perfectly apparent to those skilled in the art to which such invention relates when the foregoing description is read in connection with the accompanying drawings. 60

Having described the invention, I claim:—

In a device for the purpose set forth, a body having a handle and having one of its edges formed with projecting teeth which 70 are of a greater thickness than that of the body so that one of the edges of the said teeth extend beyond one face of the body, said teeth having their upper ends notched at a downward inclination and said body 75 having its edge opposite that provided with the teeth thickened and channeled longitudinally from the inner edge thereof to provide a depending flange, and the said channel entering the body to render this portion of the body of a less thickness than the remainder of the body, for the purpose set forth. 80

In testimony whereof I affix my signature.

JOSEPH HILSER, SR.
